UNITED STATES PATENT OFFICE.

AMOS CALLESON, OF BROOKLYN, NEW YORK.

BOTTLE-SEALING MACHINE.

1,386,313.

Specification of Letters Patent.

Patented Aug. 2, 1921.

Application filed January 23, 1920. Serial No. 353,604.

To all whom it may concern:

Be it known that I, AMOS CALLESON, a citizen of the United States, residing at Brooklyn, in the county of Kings and State 5 of New York, have invented certain new and useful Improvements in Bottle-Sealing Machines, of which the following is a specification.

My present invention relates to bottle 10 capping machines of the class in which the containers are advanced in a procession past the capping means, and it consists in certain improvements in the means for feeding the caps or other closures to the containers from 15 a source of supply with reference to which the latter move in procession, whereby the feeding of the caps to the passing containers is accomplished with uniform certainty and without the danger of producing a jam.

20 In the drawings,

Figure 1 is a side elevation, partly in section, of sufficient of a bottle capping machine to illustrate the invention;

Fig. 2 is a sectional view on line 2—2, 25 Fig. 1;

Fig. 3 is a front elevation of the super-structure;

Fig. 4 is an inside elevation of the closure-feeding chute, certain parts 26 and 32 co-30 active therewith being also shown, the former in section;

Fig. 5 is a vertical sectional view of the upper part of the chute;

Fig. 6 shows certain parts, notably the 35 chute and an opposed capping or sealing head, in section on substantially the line 6—6, Fig. 4;

Fig. 7 shows a capping member (in section) approaching and about to become 40 coupled with the lower end of the chute (appearing in plan);

Fig. 8 is a front elevation, partly in section, of the chute-controlling means;

Fig. 9 is a plan, partly in section, of said 45 means;

Fig. 10 is a plan; Fig. 11 a sectional view on line 11—11, Fig. 10; and Fig. 12 an inside elevation of one of the parts of the coupling means carried by the chute; and

50 Fig. 13 is an inside elevation and vertical sectional view of another part of said means.

I have illustrated my invention in connection with a machine of known type, to wit, in which the containers are carried 55 around by a structure rotating on a verti-

cal axis and equipped with means for attaching the closures which are caused to perform thrust movements toward and from the respective containers, one after another, by a fixed cam. The frame of the machine 60 includes a base *a* embodying at the top a housing *a'*, an upright *b* upstanding from the back of the base, and a cylinder *c* suitably affixed to the upright over the base and having an internal cam-groove *c'*; on the bottom of the housing *a'* I fix a plate *d* which is substantially triangular (see Fig. 2) and affords at *d'* a step bearing. The rotary structure aforesaid includes a vertical shaft *e* stepped in the bearing *d'*, a turret *f* fixed to the shaft and having yielding bottle supporting pads *f'* arranged in a circle at regular intervals in its top face, and a cylindrical head *g* housed in the cylinder *c*, said head having, arranged in a circle 70 and in registry with the pads *f'*, closure affixing members *h* which are arranged to reciprocate vertically in the head *g* during the rotation of the latter by being suitably engaged in the cam-groove *c'* and 75 each including any well-known type of sealing or capping head *h'* having a closure-supporting ledge *h*² and a lateral closure-admitting passage *h*³ opening radially outwardly thereof. The base is equipped with 80 a table *i* flush with the bottle supporting surface of the turret. The front of the machine being at the left in Fig. 1, the bottles are carried around by the rotary structure and the sealing or affixing of the closures 85 takes place relatively behind shaft *e*, i. e., between such shaft and upright *b*. The rotary structure may be driven from a suitably driven shaft *j* through the medium of a pinion *k* on said shaft, a gear *l* on the depending portion of the turret and a pinion *m* intermeshing with pinion *k* and gear *l* and suitably journaled on the plate *d*. I claim no part of the foregoing, *per se*.

The turret has an upstanding boss *f*² 100 formed with peripheral recesses *f*³ registering with the pads *f'*, and the boss has a recessed portion or neck *f*⁴ in which is adapted to be received a sectional collar *n* having peripheral recesses *n'* arranged to register 105 with the recesses *f'*, the sections of the collar being removably held in place by pins *o* introduced downwardly into suitable holes in the parts. To adapt the turret to receive different sizes of bottles, which oc- 110

cupy the recesses n' of the collar, collars having recesses n' of different sizes will be provided so that they can be used interchangeably. To keep the bottles upright 5 at certain points in their progress I provide arc-shaped guides p which are secured to the table i by screws r which may pass through slots in the guides to allow their adjustment toward and from the collar n .

10 The bottles to be capped proceed from the front at one side of the table to the back, around behind the shaft e , at that time being carried by the turret, and then to the front of the table at the other side thereof. To 15 convey them one after another from the point where they are deposited by the attendant on the table to the turret and from the turret to the point where, being now capped, they are again deposited on the 20 table, I provide a rotary carrier which serves to perform both these conveying operations, which feature so far as I am aware is new in this art. This carrier consists of a thin disk s whose hub member t is fixed to a vertical shaft u that is journaled in a bearing v secured to a gear casing w that projects from the housing a' , shaft u carrying a gear x in mesh with a pinion y which is journaled 25 in plate d and meshes with a gear l on the 30 turret, so that the turret and disk s rotate in the same direction. A plate z provided with a central V-shaped projection extending inwardly therefrom and having an up- 35 standing flange z' projecting from each end thereof and along its inner margin to more or less near the apex of the projection is secured to the front of the table over the disk s and forms with guides 2 secured to the 40 table means to insure the bottles remaining upright and taking the course indicated by the arrows in Fig. 2; it also serves, in co-operation with the guide p shown at the left in Fig. 2, to guide each bottle accurately to its position on the turret. For synchronizing 45 the approach of the bottles to the turret with the passing bottle pads I provide a bottle checking means which is intermittently moved to release the line of bottles approaching the turret by the projections 50 formed between the recesses of the latter—specifically by the projections formed between the recesses n' of its collar n . A lever 3 fulcrumed on a pin 4 has a toe 5 normally projecting in the path of the approaching 55 bottles, and another lever 6 fulcrumed on a stud 7 has its toe 8 normally projecting in the path of the projections on the collar n , being articulated with the lever 3 by the slot and pin connection 9; a spring 10 connecting 60 the levers normally holds them in the position stated. Each time a projection on the collar passes and moves the levers the first bottle behind the toe 5 will be released so as to be carried forward by the disk s 65 in proper time for accurate positioning of

such bottle on a bottle pad, the ensuing return of the levers causing the toe to check the next bottle in line until it is released in the same manner for deposit on the next bottle pad.

70 The machine is reversible, the structure $e-f-g$ and all parts geared therewith being adapted to rotate in either direction, so that the progress of the bottles may be either generally from right to left or left to right; therefore the parts 2—2, p and 3—6 are invertible and relatively interchangeable.

75 The hopper 11 for the closures is secured to some fixed part of the frame, as cylinder c . It is equipped with a closure delivery chute 80 and as will appear this chute is capable of a certain movement with the rotating structure $e-f-g$ (to allow time for transfer of a closure from the chute to the sealing head then in registry therewith) and back, being normally held in a definite position; it is also capable in the present construction of movement toward and from the rotary structure, partly so that when moving with said structure it shall move concentrically therewith and partly to permit access to the outlet of such chute or the inlet to the sealing head which it happens to be opposite.

85 The chute 12 has a chute extension member 13 pivoted to its upper end on an axis 14 radial with respect to rotary structure $e-f-g$, and this member is in turn pivoted to the bottom of the hopper (whose outlet 15 debouches into member 13) on an axis 16 arranged horizontally and transverse with 90 respect to axis 14, so that the chute has a universal-joint connection with the hopper and can swing laterally or inward and outward. Normally its lateral movement is in an arc concentric with shaft e , the chute having a roller 17 which upstands in a curved 95 guideway 18 (Figs. 8 and 9) formed by a plate 19 secured to the cylinder c and a frontal lip member 20, which is normally held in the position shown by a detent 21 100 but, upon shifting the detent, may be swung up on a pivot 22 to release the chute and permit it to be swung outward when access to its outlet or to a sealing head inlet is required.

105 The chute is interposed between opposed spring means consisting of a pair of springs 23 arranged in opposite housings in plate 19, removable screw plugs 24 backing the springs and closing the outer ends of the 110 housings, and pins 25 which protrude from the inner ends of the housings and bear against opposite sides of the chute and having shoulders 24' limiting their inward movement in the housings under pressure of 115 said springs, one of the pins being longer 120 than the other so that the chute is held near one of the limits of its movement afforded by guideway 18. (On reversing the machine these pins may be changed about in 125 their housings so that the chute will be nor- 130

mally held at its other limit of movement.) There is a cam lug or toe 26 on each sealing head which, as the sealing head moves around, encounters a part of the chute and 5 moves the chute along with such sealing head while the lowest closure in the former is being transferred to the latter, and to interlock the chute with such sealing head at this time in a definite relation thereto and 10 also control the feed of the closures down the chute I equip the latter as follows:

A two-part coupling device, to receive and obtain a positive hold on the toe 26, is fulcrumed on the lower end of the chute. One 15 part 27 of this device is formed to straddle the inwardly deflected lower end of the chute and has the fulcrum connection therewith, afforded by pin 28, being normally held by a spring 29 interposed between its 20 upstanding portion 27' and the chute with its cross-piece 27² normally seated on the chute (Fig. 6); this part also includes a housing 27³ at the front of upstanding portion 27' and forming therewith a vertical 25 guideway 27⁴. The cross-piece has a central locking notch 27⁵, and it is beveled off from said notch to either end (Fig. 4) to form cam surfaces 27⁶. The other part of said coupling device is a dog 30 arranged to slide 30 in guideway 27⁴, being normally held to the downward limit afforded by its stop 30' engaging the top of portion 27' of part 27 by a spring 31 arranged in housing 27³, the forwardly extending lower end or lug 30² of 35 said dog being directly over locking notch 27⁵ and rounded on its under side. Spring 31 is stronger than spring 29. A fixed coupling-breaker 32, acting to depress the part 27 when it is swung around with the chute, 40 is secured in plate 19. Pivoted in part 27 is a closure-detent 33 which is normally held by springs 34 housed in part 30 bearing down against and thus pressing or clamping the lowest closure in the line against the 45 bottom of the chute.

The machine, as shown, is arranged for left to right bottle feed, *i. e.*, clockwise movement of the bottles and sealing heads. Therefore the chute is normally held by the 50 spring means 23 in the right-hand position (Fig. 3). As each capping member approaches, being then elevated, its cam lug 26 acts wedge-fashion between part 27 and the rounded face of the lug 30² of part 30 and cams the former up out of the way; but when the cam lug overlies locking notch 27⁵, since spring 31 is stronger than spring 29, part 27 is raised by spring 31, resuming its 55 previous relation to part 30, so that the lug 26 remains locked in notch 27⁵ and so the chute is advanced with the capping member against the resistance of its spring means. The raising of part 30 removes the pressure 60 its spring 34 exerts on detent 33, in consequence of which, while the sealing head and

chute are moving together thus intercoupled, the line of closures in the chute are allowed to fall by gravity to place the lowest one on the ledge h² of the sealing head and the second one under the detent. This having been done the nearer cam surface on 70 part 27 encounters the coupling-breaker 32 and is depressed thereby (part 30 being prevented from also descending by lug 26), so that its notch 27⁵ clears the lug 26 and under 75 pressure of its spring means the chute swings back to its normal position (Fig. 1) ready to repeat the operation with the next approaching capping member. When the chute springs back it is cushioned by its 80 spring means 23, 24, 25, as will be apparent from the position of these parts as shown in Fig. 8.

The spring means controlling the position of the chute are reversible and the parts 85 concerned in coupling each capping head with the chute are formed for accomplishing the coupling and uncoupling either right or left-handed, according to the direction in which the feeding of the bottles takes place. 90

So far as I am aware it is new in the art of transferring closures in a machine substantially of the nature of that herein set forth to provide a closure delivery member, such as the aforesaid chute, a closure receiving member, such as the sealing head h, and means to support them and move one repeatedly past and in closure-transferring relation to the other, one being shiftable in said means with the other each time the 100 latter passes.

Having thus fully described my invention, what I claim as new and desire to secure by Letters Patent is:—

1. In combination, a closure delivery chute 105 member, a closure receiving member, and means to support said members and move one repeatedly past and in closure-transferring relation to the other, one of said members being shiftable in said means with 110 the other each time one of said members moves past the other.

2. In combination, a closure delivery member, a closure receiving member, and means to support said members and move one repeatedly past and in closure-transferring relation to the other, one of said members being oscillatory in said means and being shiftable by and with the other each time one of said members moves past 120 the other.

3. In combination, a closure delivery member, a closure receiving member, and means to support said members and move one repeatedly past and in closure-transferring relation to the other, one of said members being shiftable in said means with 125 the other each time one of said members moves past the other but normally held in a definite position in said means.

4. In combination, a closure-delivery member, a closure receiving means, and means to support said members and move one repeatedly past and in closure-transferring relation to the other, one of said members being shiftable in said means with the other each time one of said members moves past the other but spring held in a definite position in said means.
5. In combination, a closure delivery member, a closure receiving member, and means to support said members and move the latter repeatedly past and in closure-transferring relation to the former, said delivery member being pivotally suspended at its upper end portion in said means and shiftable therein with the receiving member each time the latter moves past the former.
6. In combination, a closure delivery member, a closure receiving member, and means to support said members and move the latter repeatedly past and in closure-transferring relation to the former, said delivery member being pivotally suspended in said means and shiftable therein with the receiving member each time the latter moves past the former but normally held in a definite position in said means.
7. In combination, a closure delivery member, a closure receiving member, and means to support said members and move the latter in a definite course repeatedly past and in closure-transferring relation to the former, said delivery member being shiftable in said means in a path substantially lengthwise of said course and being so shiftable with the receiving member each time the latter moves past the former and being also adapted to be moved crosswise of said path.
8. In combination, a closure delivery member, a closure receiving member, means to support said members and move the latter repeatedly past and in closure-transferring relation to the former, the delivery member being shiftable in said means with the receiving member each time the latter moves past the former, and opposite spring means holding said delivery means normally against shifting.
9. In combination, a closure delivery member, a closure receiving member, and means to support said members and move one repeatedly past and in closure-transferring relation to the other, one of said members being shiftable in said means and said members having means to temporarily intercouple them each time one of said members moves past the other.
10. In combination, a closure delivery member, a closure receiving member, and means to support said members and move one repeatedly past and in closure-transferring relation to the other, one of said members being shiftable but normally held in a definite position in said means and said members having means to temporarily intercouple them each time one of said members moves past the other.
11. In combination, a closure delivery member for a line of closures, a closure receiving member, and means to support said members and move one repeatedly past and in closure-transferring relation to the other, one of said members being shiftable in said means and said members having means, controlling the transfer of the closures from one to the other of them, to temporarily intercouple them each time one of said members moves past the other.
12. In combination, a closure delivery member for a line of closures normally subjected to an evicting force, a check normally opposing the eviction of the closures, a closure receiving member, and means to support said members and move one repeatedly past and in closure-transferring relation to the other, one of said members being shiftable in said means and said members having means to temporarily intercouple them and release the check each time one of said members moves past the other.
13. In combination, a closure supply member, a closure receiving member, means to support said members and move the latter repeatedly past and in closure-transferring relation to the former, and a closure delivery member having a pivotal connection with and movable relatively to the supply member in approximately the same direction as and with the receiving member each time the latter moves past the supply member.
14. In combination, a closure supply member, a closure receiving member, means to support said members and move the latter repeatedly past and in closure-transferring relation to the former, and a closure delivery member movable relatively to the supply member in approximately the same direction as and with the receiving member each time the latter moves past the supply member but normally held in a definite position.
15. In combination, a closure supply member, a closure receiving member, means to support said members and move the latter repeatedly past and in closure-transferring relation to the former, and a closure delivery member movable relatively to the supply member in approximately the same direction as the receiving member each time the latter moves past the supply member but spring held in a definite position.
16. In combination, a closure supply member, a closure receiving member, means to support said members and move the latter repeatedly past and in closure-transferring relation to the former, a closure-delivery member movable relatively to the supply member in approximately the same direction as and with the receiving member each time the latter moves past the supply member but normally held in a definite position.

the latter moves past the supply member, and opposite spring means holding said delivery means normally against such movement.

17. In combination, a closure supply member, a closure receiving member, means to support said members and move the latter repeatedly past and in closure-transferring relation to the former, and a closure delivery member movable in a definite course relatively to the supply member in approximately the same direction as and with the receiving member each time the latter moves past the supply member, said delivery means being normally held in but movable out of
- 10 said course.
18. In combination, a closure supply member, a closure receiving member, means to support said members and move the latter repeatedly past the former, a closure delivery member for a line of closures movable relatively to the supply member in approximately the same direction as the receiving
- 15
- 20

member, and means, controlling the transfer of closures from the delivery to the receiving member, to temporarily interconnect them 25 for movement together each time the latter moves past the supply member.

19. In combination, a closure supply member, a closure receiving member, means to support said members and move the latter 30 repeatedly past the former, a closure delivery member for a line of closures normally subjected to an evicting force, said delivery member being movable relatively to the supply member in approximately the same direction 35 as the receiving member, a check normally opposing the eviction of the closures, and means to temporarily interconnect the delivery and receiving members and release the check each time the latter moves past the supply member.

In testimony whereof I affix my signature.

AMOS CALLESON.
